JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

IGNITION APPARATUS.

1,330,619.

Specification of Letters Patent. Patented Feb. 10, 1920.

Application filed April 26, 1915, Serial No. 23,979. Renewed June 9, 1919. Serial No. 303,000.

To all whom it may concern:

Be it known that I, JOSEPH BIJUR, a citizen of the United States, and residing at New York, in the county of New York and 5 State of New York, have invented a new and Improved Ignition Apparatus, of which the following specification is a full disclosure.

This invention relates to ignition apparatus for internal combustion engines. One 10 of the objects thereof is to provide simple and practical means for igniting the charges of internal combustion engines, characterized by improved efficiency in action. Another 15 object is to provide apparatus of the above type in which the time of ignition is automatically proportioned to the speed of the engine. Another object is to provide ignition apparatus which automatically varies 20 the time of sparking to suit certain conditions of running. Other objects will be in part obvious and in part pointed out hereinafter.

The invention accordingly consists in the 25 features of construction, combinations of elements, and arrangement of parts which will be exemplified in the construction hereinafter described and the scope of the application of which will be indicated in the following claims.

Referring now to the accompanying drawing in which is shown one of various possible embodiments of the various features of this invention, Figure 1 is a diagrammatic plan of the same, certain parts being cut away to disclose the structure more clearly. Fig. 2 is a diagrammatic view indicating the action of certain parts.

Similar reference characters refer to similar parts throughout both views of the drawing.

Referring now to Fig. 1 of the drawing, there is diagrammatically indicated at 1 an internal combustion engine, the secondary 45 ignition circuit 2 being operatively related thereto through spark plugs and the like. The secondary coil 3 positioned in circuit 2 is inductively related to a primary coil 4 to form conjointly an induction coil. A storage 50 battery or other source of current 5 is provided with a circuit comprising the switch 6 and coil 4 as well as the conductors 7 and 8 leading through a casing 9 and insulated therefrom as indicated at 10. This casing 55 is so mounted as to swing about the axis 11

of a shaft 12, preferably by means of a tubular hub indicated in dotted lines at 13.

Shaft 12 is provided with a cam 14 having two or more similar parts 15. This cam coacts with a lever 16 pivoted at 17 within 60 the casing, a suitable roller 18 being preferably provided to reduce friction. The roller 18 is held against the cam as by means of a flat spring 19, and shaft 12, being driven from the engine 1, oscillates the lever 16 as 65 the roller rides over the cam portions 15. It will be understood that a suitable gearing is employed between the shaft 12 and the engine so that the parts 15 cause an oscillation of the lever 16 for each charge to be exploded in the engine cylinders. 70

The conductors 7 and 8 are respectively connected with the pivot pin 17 and a pivot pin 20 of a lever 21. Mounted upon lever 21 is a contact 22 which coacts with a contact 23 75 adjustably mounted upon the lever 16, and it will be seen from the above circuits that as these contacts separate the current is interrupted in coil 4, giving rise to an impulse in the secondary coil 3. It is to be noted 80 that a condenser 24 is preferably bridged about this point of interruption in order to reduce sparking. Contact 22 is normally urged against the contact 23 by spring 25 which is of sufficient strength to cause a firm 85 engagement but not to overcome spring 19 and urge roller 18 away from the cam. In this embodiment of the invention, there is formed upon the end of lever 21, remote from contact 22, a weight 26, the movement 90 of which is limited by an adjustable stop screw 27 in the casing 9.

Considering now the action of the above described devices and assuming the casing 9 to be held in position by spring 28 urging 95 the arm 29 against a set screw 30, it will be seen that, switch 6 being closed and the engine being in action, there is a constant oscillation of the lever 16 due to the action of the cam parts 15 as above described. As 100 each oscillation occurs, and the roller 18 starts to travel away from the axis 11, the contact 22 first follows the contact 23. This following movement, however, due to the substantial inertia of the weight 26 and the 105 comparative weakness of spring 25, is not rapid and at a certain stage of speed or acceleration of the lever 16 the contact 23 leaves contact 22, thus interrupting the circuit through the coil 4. At a later stage, after 110

the interruption has occurred, the contacts 22 and 23 again swing into engagement and the parts again assume the position indicated in the drawing, this cycle of actions 5 being repeated each time a cam portion 15 coacts with the roller 18.

As above noted, the time of interruption of the circuit depends upon the degree of speed or, in this case, acceleration, of the 10 swinging movement of the lever 16. This fact is utilized to attain an important result. The curve 31 of each cam portion 15 is so formed that the radii from its surface to the axis 11 increase, and increase at an increasing rate. Referring to Fig. 2 of the drawings, this curve 31 is for the sake of rendering this matter clear, developed to gain a similar motion with a rectilinear movement. Assuming that the curve 31 in Fig. 2 travels 15 in the direction indicated by the arrow 32 and that the roller 18 be moved thereby in the direction indicated by arrow 33, this curve is thus upwardly concave and hence, with a regular and uniform motion of the 20 curve, the part 18 would be raised not only with increasing speed but with increasing acceleration, and the curve is so shaped as to get this effect. Assuming now that a certain speed or acceleration of the contact 23 25 is required to have it leave contact 22 in their upward movement, there is, of course, a corresponding speed requisite with the roller 18. To recur for the moment to Fig. 2, and assume that a certain upward speed 30 of the part 18 is required, this speed will be attained at different points of the curve in accordance with the speed of movement of the latter toward the right. For example, if the curve 31 in Fig. 2 will move 35 at a moderate rate toward the right, the critical upward speed of the part 18 might be reached at the dotted position 34. If the speed of movement of the curve 31 were extremely rapid, the critical speed of part 18 40 might be reached at 35 and, on the other hand, if it were extremely slow, the part 18 might not reach its critical rate until it encountered a very steep portion of the curve as at 36. Returning now to Fig. 1 of the 45 drawing, this same action holds true and the angular position of the cam 14 at which it imparts sufficient speed to contact 23 to cause the latter to leave contact 22, will depend upon the speed with which the shaft 50 12 is rotated or, in other words, will depend upon the engine speed. For example, at a high engine speed the cam portion 15 might become effective to break the ignition circuit when its radius 37 contacts the roller 18; that is, shortly after the latter has left the concentric portion 38. On the other hand, if the speed of the engine were extremely slow, the cam portion 15 might not cause interruption until its radius 39 had 55 coacted with the roller 18.

It will thus be seen that according as the speed of the engine becomes greater, the time of sparking is automatically advanced and by a proper proportion of the curve and size of the parts, this advance may be 70 just such as is desired for smooth running of the engine.

It is to be noted that with the above embodiment something more than a mere increase in speed of swinging of the lever 16 is 75 required, inasmuch as spring 25 will slowly accelerate weight 26, but the curve as above noted may be so proportioned that the rate of acceleration as well as rate of speed will be such as to cause a separation of the contacts automatically at the proper point, in accordance with the engine speed. It is also to be noted at this point, that although certain advantages inhere in the above inertia acting retarding means, nevertheless other 85 devices, such as a dash pot or a voltage magnet connected across the battery, might be employed to accomplish this end.

Considering now certain stages of motion of the engine, there are here provided means 90 for rendering the action of the ignition apparatus automatic in the face of changes other than those of engine speed.

Diagrammatically indicated at 40 is the fuel controlling apparatus for the engine, 1, 95 preferably a rod leading to the engine throttle. Rigidly pinned to this rod is an arm 41 beneath which is mounted a dash pot 42. Arm 41 is provided with a downward extension 43 terminating in a piston 44 fitting 100 the dash pot 42. Pivoted beneath dash pot 42 at 45 is a sleeve latch 46 which is normally supported by a light spring 47 connected between the end of the arm 41 and weight 46^a on the latch, as shown. Passing 105 loosely through an opening 48 in the latch 46 is a rod 49 which is pivotally connected with an arm 50 of the casing 9. Assuming now that the gas supply of the engine be increased as by a movement of the part 40, 110 as is indicated by arrow 51, there is a tendency of the latch 46 with its weight 46^a to lag, due to its inertia, into the position indicated in dotted lines at 52. In this position it grips about or binds on the rod 49, 115 forcing it upward and swinging the casing 9 about the axis 11, this being permitted by the spring 28. This action swings the roller 18 with the casing in the direction of rotation of cam 14 and hence retards the time 120 of actuation of the interrupting device with respect to the cycle of the engine. In this manner, the first few explosions following an increase of gas supply are automatically provided with a delayed or retarded ignition until the engine can come up to the speed corresponding with such supply.

After the part 40, assuming it to have been moved as above, has come to rest, the dash pot 42 slowly moves from the piston 130

44 to a sufficient extent to relieve the hold of latch 46 on rod 49. The parts are then in the position indicated in Fig. 1 of the drawing in full lines, with the exception that the 5 dash pot and latch are slightly lower and the spring 47 slightly extended. The latter, however, slowly draws up the dash pot on piston 44 and returns the parts to their normal position. It is to be noted that a sudden 10 movement of rod 40 in the opposite direction, that is, to cut down or cut off gas, has no effect on the part 49 and the devices connected therewith.

It will thus be seen that there is provided 15 an automatically timed circuit interrupting device and it is to be noted that the term "interrupt" is used herein in a broad sense to denote an interruption of effective flow, whether the current be entirely cut off or 20 not. It is also to be noted that the features of the above apparatus which deal with automatic regulation of the time of ignition for engine speed are of value without the device for affecting it by increase of gas 25 supply and, on the other hand, the latter device is of value with other forms of automatically or manually timed interrupters, but there are certain advantages in using both of these devices in conjunction one with 30 another.

It will thus be seen that there is provided apparatus in which the several objects of this invention are achieved.

As many changes might be made in the 35 above construction, and as many apparently different embodiments might be made of this invention without departing from the scope thereof, it is intended that all features herein described or shown in the accompanying 40 drawings shall be interpreted as illustrative and not in a limiting sense.

Having thus revealed this invention, I claim as new and desire to secure the following combinations of elements, or equivalents 45 thereof, by Letters Patent of the United States:

1. In ignition apparatus for internal combustion engines, in combination, an electric circuit comprising a pair of coacting contacts, an engine-driven device adapted with 50 uniform engine speed to move one of said contacts in a direction away from the other at an increasing rate of speed, and means adapted to cause the other contact to follow the same at a restricted rate of speed.

2. In ignition apparatus for internal combustion engines, in combination, an electric circuit comprising a pair of coacting contacts, an engine-driven device adapted with 55 uniform engine speed to move one of said contacts in a direction away from the other at an increasing rate of speed, means adapted to cause the other contact to follow said first contact, and means adapted to retard the 60 following action of said second contact.

3. In ignition apparatus for internal combustion engines, in combination, an electric circuit comprising a pair of coacting contacts, an engine-driven device adapted with uniform engine speed to move one of said 70 contacts in a direction away from the other at an increasing rate of acceleration, and means adapted to cause the other contact to follow at a restricted rate of acceleration.

4. In ignition apparatus for internal combustion engines, in combination, an electric circuit comprising a pair of coacting contacts, an engine-driven device adapted with uniform engine speed to move one of said 75 contacts in a direction away from the other at an increasing rate of acceleration, means adapted to cause the other contact to follow said first contact, and means adapted to retard the following action of said second contact.

5. In ignition apparatus for internal combustion engines, in combination, an interrupting device for an electric circuit, comprising a pair of relatively separable coacting contacts, and means including an inertia-controlled member governing the time of separation of said contacts.

6. In ignition apparatus for internal combustion engines, in combination, an internal combustion engine, an interrupting device 95 for an electric circuit in the ignition apparatus of said engine, said interrupting device being driven from said engine and said electric circuit comprising a pair of relatively separable coacting contacts, and means including an inertia-controlled member governing the time of separation of said contacts in accordance with the speed of said engine.

7. In ignition apparatus for internal combustion engines, in combination, an engine, a rotatable cam driven from said engine, a pair of relatively separable coacting contacts, means driven from said cam adapted to separate said contacts, and means adapted 100 automatically to change, in accordance with the speed of the engine, the point of said cam which is effective to separate said contacts.

8. In ignition apparatus for internal combustion engines, in combination, an electric circuit comprising a pair of contacts, both of which are movable in the same direction, said contacts being relatively separable to interrupt said circuit, a cam, and means 115 driven from said cam adapted to move one of said contacts, said cam being so shaped as with a uniform rate of movement to cause an increasing rate of movement of the contact moved thereby.

9. In ignition apparatus for internal combustion engines, in combination, an electric circuit comprising a pair of contacts both of which are movable in the same direction, said contacts being relatively separable to 120

interrupt said circuit, a cam, means driven from said cam adapted to move one of said contacts, said cam being so shaped as with a uniform rate of movement to cause an increasing rate of movement of the contact moved thereby, and means adapted to cause the remaining contact to follow at a restricted rate of speed.

10. In ignition apparatus for internal combustion engines, in combination, an electric circuit comprising a pair of contacts both of which are movable in the same direction, said contacts being relatively separable to interrupt said circuit, a cam, means driven from said cam adapted to move one of said contacts, said cam being so shaped as with a uniform rate of movement to cause an increasing rate of movement of the contact moved thereby, means adapted to cause the remaining contact to follow said first contact, and means adapted to retard said following movement.

11. In ignition apparatus for internal combustion engines, in combination, an electric circuit comprising a pair of contacts both of which are movable in the same direction, said contacts being relatively separable to interrupt said circuit, a cam, means driven from said cam adapted to move one of said contacts, said cam being so shaped as with a uniform rate of movement to cause an increasing rate of movement of the contact moved thereby, means adapted to cause the remaining contact to follow said first contact, and inertia-governed means tending to restrict said following action.

12. In ignition apparatus for internal combustion engines, in combination, an internal combustion engine, an electric circuit in the ignition apparatus of said engine comprising a pair of relatively separable coacting contacts, a cam driven from said engine, a device coacting with said cam to move one of said contacts in a direction away from the other, said cam being shaped to present a surface of sharply increasing steepness to the device with which it coacts and having its effective surface formed on such a curve as rapidly to increase the rate of movement of said first contact with a uniform rate of movement of the cam, means tending to cause said second contact to follow said first contact, and means adapted to retard said following action.

13. In ignition apparatus for internal combustion engines, in combination, an internal combustion engine, means adapted to cause ignition of the charges of said engine, means controlling the fuel supply of said engine, and means adapted automatically to retard the time of ignition as the fuel supply is increased.

14. In ignition apparatus for internal combustion engines, in combination, an internal combustion engine, means adapted to

cause ignition of the charges of said engine, manually controlled means controlling the fuel supply of said engine, and means adapted automatically to give a temporary retardation to the time of ignition of said engine as its fuel supply is increased thereby.

15. In ignition apparatus for internal combustion engines, in combination, an internal combustion engine, means adapted to cause ignition of the charges of said engine, means controlling the fuel supply of said engine, means adapted automatically to give a temporary retardation to the time of ignition of said engine as its fuel supply is increased, and means adapted automatically to restore said time of ignition.

16. In ignition apparatus for internal combustion engines, in combination, an internal combustion engine, means adapted to cause ignition of the charges of said engine, means controlling the fuel supply of said engine, means adapted automatically to retard the time of ignition as the fuel supply is increased, and means adapted automatically to advance the time of ignition as the speed of the engine increases.

17. In ignition apparatus for internal combustion engines, in combination, an internal combustion engine, means adapted to cause ignition of the charges of said engine, means controlling the fuel supply of said engine, means adapted automatically to give a temporary retardation to the time of ignition of said engine as its fuel supply is increased, and means adapted automatically to advance the time of ignition as the speed of the engine increases.

18. In ignition apparatus for internal combustion engines, in combination, an internal combustion engine, means adapted to cause ignition of the charges of said engine, means controlling the fuel supply of said engine, means adapted temporarily to connect said fuel controlling device with said ignition device as the supply of fuel is increased and move said ignition device to retard the time of ignition, means adapted automatically to break said connection subsequent to the movement of the fuel controlling device, and means adapted to restore the parts to their original position.

19. In ignition apparatus for internal combustion engines, in combination, an internal combustion engine, means adapted to cause ignition of the charges of said engine, means controlling the fuel supply of said engine, means adapted temporarily to connect said fuel controlling device with said ignition device as the supply of fuel is increased and move said ignition device to retard the time of ignition, means adapted automatically to break said connection subsequent to the movement of the fuel controlling device, means adapted to restore the parts to their original position, and means adapted

automatically to advance the time of ignition as the speed of the engine increases.

20. In ignition apparatus for internal combustion engines, in combination, an internal combustion engine, a member controlling the time of ignition of said engine, a member controlling the fuel supply of said engine, a device adapted to permit free movement of said first member in either direction, and a connection between said device and said second member adapted to cause said device to make connection with said first member upon said second member being moved in a direction to increase the fuel supply of said engine.

21. In ignition apparatus for internal combustion engines, in combination, an electric circuit comprising a pair of coacting contacts, an engine-driven device adapted with uniform engine speed to move one of said contacts in a direction away from the other at an increasing rate of speed, means adapted to cause the other contact to follow the same at a restricted rate of speed, means

adapted to vary the time of effective action of said engine-driven device, means adapted to control the fuel supply of the engine, and means acting upon said time controlling device and adapted automatically to retard the time of ignition as the fuel supply of said engine is increased.

22. In ignition apparatus for internal combustion engines, in combination, an electric circuit, a circuit-interrupting device adapted to become operative upon one of its members attaining a certain speed, and engine driven means adapted with uniform engine speed to move said member at an increasing rate of speed from its circuit-closing position.

In witness whereof, I hereunto subscribe my name, as attested by the two subscribing witnesses.

JOSEPH BIJUR.
